(57) **CLAIM**

The ornamental design for a multi-tool case, as shown and described.

DESCRIPTION

FIG. 1 is a front perspective view of a multi-tool case, showing my new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a right side elevation view thereof;

FIG. 7 is a left side elevation view thereof; and,

FIG. 8 is a front perspective view illustrating a flap in an open position according to FIG. 1.

The broken line showing of the environment is for illustrative purpose only and forms no part of the claimed design.

1 Claim, 6 Drawing Sheets
